(57) **CLAIM**

The ornamental design for a firearm stock, toy and/or replica, as shown and described.

DESCRIPTION

FIG. 1 is a left, front, top perspective view of the firearm stock, toy and/or replica;

FIG. 2 is a right rear, bottom perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a top view thereof;

FIG. 8 is a bottom view thereof;

FIG. 9 is a left, front, top perspective view of the firearm stock, toy and/or replica in a folded state;

FIG. 10 is a left, front, top perspective view of the firearm stock, toy and/or replica in an extended state;

FIG. 11 is a right rear, bottom perspective view thereof;

FIG. 12 is a front elevation view thereof;

FIG. 13 is a back elevation view thereof;

FIG. 14 is a left elevation view thereof;

FIG. 15 is a right elevation view thereof;

FIG. 16 is a top view thereof; and,

FIG. 17 is a bottom view thereof.

The broken lines immediately adjacent to the shaded areas depict the bounds of the claimed design, while all other broken lines are directed to the environment. The broken lines form no part of the claimed design.

The “Magpul” lettering and icon forming part of the disclosure is a registered trademark of Magpul Industries Corp.

1 Claim, 17 Drawing Sheets
